FRAME BUILDING DISMANTLING TOOL

Henry Phillip Fehler, Wolseley, Saskatchewan,
Canada

Application February 6, 1950, Serial No. 142,586

4 Claims. (Cl. 254—131)

1
My invention relates to dismantling tools, having particular reference to an all purpose tool for use in wrecking frame buildings.

In the art to which the invention relates it has been proposed to provide wrecking bars and other tools for removal of boards, studding and the like in the dismantling of frame buildings. In such devices no provision is made for application of a uniform pressure across the full width of the part being removed, such as a board, to avoid splitting the board or breaking it.

The present invention contemplates improvements in frame building wrecking and dismantling tools by provision of means for application of uniform pressure over the whole face of a board or the like that is nailed to another part of the building from which it is to be disengaged. The tool further provides an adjustable attachment by which a limitation may be imposed on the extent to which a board or the like is pried loose from a stud, and a further attachment by which application of the tool may be limited to one board at a time.

One of the objects of the invention is accordingly to provide an improved frame building dismantling or wrecking tool adapted for application of pressure to the full width of a board or the like in disengaging the board from a part to which it is nailed.

A further object of the invention is to provide in a building dismantling tool means by which a limitation may be imposed on the extent of disengagement of a board or the like from a part of the building to which it is nailed.

A still further object of the invention is to provide in a dismantling tool adjustable means by which pressure applied by the tool in disengaging a board or the like from a part to which it is nailed may be limited to a single board.

Other features and advantages of the invention will become apparent by reference to the accompanying description taken in conjunction with the drawings wherein like characters of reference indicate like parts throughout the several views and wherein:

Fig. 1 is a side view of a tool embodying my improvements and shown partly sectioned.

Fig. 2 is a detail view of the heel plate with fragment of the pressure applying arm.

Fig. 3 shows a side view of the width adjuster attachment taken by itself.

Fig. 4 shows a detail view of the depth adjusting attachment taken by itself.

Fig. 5 shows a side view of the tool complete as it would appear in use, with fragments of boards and stud included.

2
Having reference to the drawing my improved frame building dismantling tool provides a tubular handle bar 1 with pressure applying arm 2 fixed thereto at an acute angle to the handle bar and a brace member 3 between the arm 2 and bar 1, the brace member attaching in right angular relation to the pressure applying arm.

At the junction of the handle bar 1 and pressure applying arm 2 is a heel plate 4 fixed thereto and providing chisel points 5—5 projecting laterally of the handle bar and pressure applying arm, the chisel points providing flat faces, as at 6, lying substantially on a line with the under surface of the pressure applying arm.

The tool may be used without the attachments, to be hereinafter described, and as above described may be applied in the dismantling of a building. The tool has a variety of uses and methods of application to meet the various problems presented in disengaging parts of the building nailed to other parts, as will readily suggest itself to one skilled in the art.

In the simple application of the tool the one or other chisel point 5 is engaged behind a stud, such as the stud 7 illustrated in Figure 5, and with the arm 2 lying substantially flat against a board 8 to be disengaged, or, as in a starting series of boards, a chisel end of the heel may be driven between a board and its stud. By pressure on the handle 1 in the direction indicated by the arrows the board 8 may be pried from the stud 7. The pressure exerted on the arm 2 is across the face of the board eliminating danger of splitting the board.

In the use of the tool it is generally desirable to pry a board only partly off until the board has been similarly disengaged from the next stud, particularly where the studding is closely spaced. For this I provide a depth limiting attachment, separately illustrated in Figure 4.

This consists of a short piece of angle plate 9 engaged on the brace member 3 by a U clamp 10, with an insert 11 interposed between the clamp and member 3. The clamp is secured to the angle plate 9 by nuts 12 threaded on the legs of the clamp, by which the clamp may be loosened to shift the angle plate along the member 3 and attach it at such distance from the arm 2 as is required.

Referring again to Figure 5, when the board 8 has been pried loose as far as is desirable on that application of the tool, the angle plate 9 coming in contact with the stud 7 stops further downward pressure of the arm 3 fulcrumed on the heel plate 4. At this stage the tool may be applied at the next stud, or the nails

removed from the stud from which the board is partially disengaged.

It has further been found desirable to limit application of the arm 2 to one board at a time. For this I provide a width adjuster, separately illustrated in Figure 3. This consists of a bar 13 bent U-shaped at one end, as at 14, with clamping bolt 15 having a nut 16 by which the U portion of the bar may be secured frictionally in any desired position of adjustment along the arm 2. At the other end of the bar 13 is a bent finger 17 engageable loosely in a suitable opening in the tubular handle 1, the end portion 18 of the finger lying within the bore of the handle.

In the use of the adjuster bar 13, the bar is set with the U portion 14 fixed to the arm 2 a distance from the free end of the arm 2 corresponding to the width of the board 8 so that pressure of the arm 2 will apply to the board only. In Figure 5 a partially removed board 19 is also shown.

There is further included a point 26 for the free end of the handle 1, this point being a separate element and removable, and including a shank 21 of reduced diameter insertable in the bore of the tubular handle. This permits reversing the tool to use the pointed end for prying where required.

While I have herein disclosed a preferred embodiment of my invention, changes in the construction and arrangement of parts would be conceivable, and in so far as such changes come within the spirit and scope of the invention as defined in the appended claims they would be considered a part hereof.

Having thus particularly described and ascertained the nature of my invention, what I claim and wish to secure by Letters Patent is:

1. A frame building dismantling tool providing a handle with pressure applying arm fixed thereto at one end thereof at an acute angle in rela-

tion to the handle, and a heel plate at the junction of said arm and handle, fixed to the outer side extending transversely thereof and projecting outwardly on both sides of the handle and pressure applying arm, said heel plate having tapered end portions terminating in sharpened edges.

2. A frame building dismantling tool comprising a handle, a pressure applying arm fixed to the handle at one end thereof at an acute angle in relation to the handle, a brace member between the pressure applying arm and handle, and a heel plate at the junction of said arm and handle, fixed to the outer side extending transversely thereof and projecting outwardly on both sides of the handle and pressure applying arm, said heel plate having tapered ends terminating in sharpened edges.

3. A device as defined in claim 2 and including a depth adjusting attachment, comprising a plate with means attaching the plate on the brace member projecting laterally thereof, said means being adjustable lengthwise on the brace member.

4. A device as defined in claim 2 and including a width adjusting attachment comprising a bar with means on the bar detachably engaging the handle, said bar providing a U bent portion engaging the pressure applying arm and means for clamping the U bent portion to the pressure applying arm adjustable thereon.

HENRY PHILLIP FEHLER.
